DESIGN FOR A GAMING DEVICE

John E. Tolman and Felix A. Subject, Yuba City, Calif.

Application May 12, 1933. Serial No. 48,094

Term of patent 3½ years

To all whom it may concern:

Be it known that we, JOHN E. TOLMAN and FELIX A. SUBJECT, citizens of the United States, residing at Yuba City, in the county of Sutter and State of California, have invented a new, original, and ornamental Design for a Gaming Device, of which the following is a specification, reference being had to the accompanying drawing, forming part thereof.

The figure on the drawing is a perspective view of a gaming device showing our new design.

We claim:

The ornamental design for a gaming device, as shown.

JOHN E. TOLMAN.
FELIX A. SUBJECT.
